United States Patent Office.

EDWARD M. JUDD, OF WOLCOTTVILLE, CONNECTICUT.

Letters Patent No. 95,232, dated September 28, 1869; antedated September 11, 1869.

IMPROVED SPRING CURTAIN-ROLLER.

The Schedule referred to in these Letters Patent and making part of the same.

To all whom it may concern:

Be it known that I, EDWARD M. JUDD, of Wolcottville, in the county of Litchfield, and State of Connecticut, have invented and made a certain new and useful Improvement in Spring Curtain-Rollers; and I do hereby declare the following to be a full, clear, and exact description of the said invention, reference being had to the annexed drawing, making part of this specification, wherein—

Figure 1 is a longitudinal section of the roller and parts sustaining the helical spring;

Figure 2 is a view of the block for holding the inner end of the helical spring;

Figure 3 is the ratchet and stationary axis; and

Figure 4 is the disk that is set into the end of the roller.

Figure 5 is an elevation of the ratchet and stationary axis.

Similar marks of reference denote the same parts.

Curtain-fixtures have heretofore been made with a helical wire spring for revolving the roller and winding up the curtain.

In this character of curtain-fixtures a pawl has been provided to drop into a notch or cam-tooth, and hold the shade or curtain, by preventing the roller revolving.

In this character of spring-roller the stationary axle upon which the roller revolves, has extended through the helical spring, to a block provided at the inner end, forming a centre for said axle, and also holding the inner end of the spring.

My invention allows the stationary axle of the roller to be short, so that the spring will not have anything inside of it, and the parts will be more easily constructed and applied.

In the drawing—

a represents the wooden roller, with any ordinary end, *b*, to revolve in a bracket, *c*.

At the other end of the roller is a hole bored, into which the helical spring *d* is introduced.

The spring *d*, previous to its insertion, is attached, at one end, to the block *e*, that is of a diameter to fit the interior of the hole in the roller, and there are projecting points 2, cast with the block around its pe-

riphery, so that the said block *e* will be firmly fixed to the roller, by driving the same down into the hole in the roller, and, for this purpose, a metal rod may be introduced through the spring *d*.

The stationary axis of the roller is made of metal, cast with the ratchet or cam-disk *i*, on one side of which the projecting axis 3 is fitted for the outer end of the spring *d* to be connected with, and on the other side, the axis is flattened or formed polygonal, at 4, to enter the bracket *f*, so that it will be held from turning.

The roller-end revolving around the axle 3, is made of two parts—the disk *h*, that sets into a recess in the end of the wooden roller *a*, and is kept from working loose by the projecting points 5, and the cap *k* that sets over the end of the roller.

The cam-disk *i* is between these parts *h* and *k*, and they are all held in position, relatively to each other, by the cap *k*, but the roller and its parts can turn freely upon the axis 3, as the curtain is drawn down or again rolled up by the action of the spring.

The pawl *o* is hung within slots or mortises, provided for it in the roller *a* and disk *h* and cap *k*, and acts against the ratchet or cam *i*, to hold the curtain, or said pawl is relieved by the centrifugal action, in allowing the blind to roll up.

By my improved construction, the parts can be much more easily made than heretofore, and are less liable to injury in use.

What I claim, and desire to secure by Letters Patent, is—

1. The disk *h* and cap *k*, receiving between them the cam or ratchet *i* of the axle 3, as and for the purposes specified.

2: The metal block *e*, with its projecting points 2, for connecting the inner end of the spring to the roller, as set forth.

In witness whereof, I have hereunto set my signature, this 16th day of February, A. D. 1869.

E. M. JUDD.
